GRINDING MACHINE

Frederick S. Haas and Winthrop Trible, Cincinnati, Ohio, assignors to Cincinnati Grinders Incorporated, Cincinnati, Ohio, a corporation of Ohio

Application June 1, 1937, Serial No. 145,729

15 Claims. (Cl. 51—103)

This invention relates to improvements in grinding machinery and has particular reference to an improved mechanism for controlling the cycle of operation of the several shiftable parts 5 of the machine.

One of the principal objects of the present invention is the provision of an improved control mechanism for insuring proper sequential work positioning and performance of the grinding 10 operation.

A further object of the present invention is the provision of a combined hydro-electrical control mechanism for controlling the positioning of the work within the grinding machine, the performance of the grinding operation and the subsequent removal of work from the grinding position preparatory to substitution of the new piece 15 to be machined.

An additional object of the present invention is 20 the provision in connection with a machine of the centerless type of novel mechanism for insuring proper positioning and prerotation, particularly in conjunction with extremely large and heavy work pieces prior to the inception of the 25 grinding operation.

An additional object is the provision in connection with a multiple grinding wheel centerless grinder having independent wheel head adjustments of an improved automatic control 30 mechanism for determining the positioning and rotation of the work which will insure maintenance of the work in proper grinding position until all of the grinding wheels have completed their respective functions.

35 A further object of the invention is the provision of an improved work rotating mechanism and control therefor, particularly adapted for use in driving large work pieces while supported within the throat of a centerless grinder.

40 Other objects and advantages of the present invention should be readily apparent by reference to the following specification, considered in conjunction with the accompanying drawings forming a part thereof and it is to be understood 45 that we may make any modifications in the specific structural details hereinafter disclosed within the scope of the appended claims without departing from or exceeding the spirit of the invention.

50 Figure 1 is a side elevation of a machine embodying the present invention.

Figure 2 is a plan view thereof.

Figure 3 is a sectional view as on the line 3—3 of Figure 2.

55 Figure 4 is a view partly in elevation and partly

in section on the line 4—4 of certain of the work supporting and controlling mechanism as viewed from the left of Figure 3.

Figure 5 is a longitudinal sectional view through the work driving mechanism as on the line 5—5 of Figure 2.

Figure 6 is a fragmentary sectional view of the work rest blade.

Figure 7 is a fragmentary sectional view of the rack and pinion actuator for the elevating mechanism.

Figure 8 is a sectional view illustrating the infeed controlling cam and associated controls.

Figure 9 is a diagrammatic view of the hydraulic controls for the work elevating and rotating mechanisms illustrating the position occupied by the parts when in work clamping position.

Figure 10 is a diagrammatic view illustrating the position of the control valves for the work driver when the latter is in released or inoperative position.

Figure 11 is a diagrammatic view of the essential portion of the electrical controls of the machine as respects the present invention.

In the drawings in which similar characters of reference are employed to denote corresponding parts throughout the several views:

The numeral 15 designates the main base or bed of the machine, preferably imbedded in a 30 suitable concrete or like foundation 16. By reference particularly to Figures 2 and 4 of the drawings it will be noted that the present machine is particularly designed for grinding cylindrical surfaces on portions of quite large work 35 pieces, as for example, the complete rear axle housing of a motor vehicle or the like. It will, therefore, be understood that the parts in question and to be controlled are quite massive and present problems not existing with ordinary centerless grinders designed for operation upon relatively small or easily handled parts.

Mounted on the bed 15 is a slide 17 carrying the regulating wheel 18 for engagement with one of the cylindrical portions 19 of the work 45 piece. It is to be understood that two such portions 19 are simultaneously ground and that the regulating wheel units, except for their right and left hand type, are substantially duplicates one of the other, said wheels being rotated as by motors located at 20. The regulating wheel slides are individually adjustable as by the pilot wheels 21 and adjusting screws 22 for general positioning purposes.

Mounted on the base 15 in opposition to each 50

regulating wheel unit is a grinding wheel unit including a slide 23 movable toward and from its opposed regulating wheel 18 to compensate for wear or variation in size of the grinding wheel. This slide is provided with a trunnion at 24 about which the base 25 is oscillatable. This base supports in eccentric relation to the trunnion the spindle 26 for the grinding wheel 27, these axes being so related that tilting of the base 25 about the trunnion axis 26 will cause in and out movement of the periphery of the grinding wheel with respect to the regulating wheel and thus to the portion 19 of the work disposed therebetween. The motor at 28 on the base 25 oscillatable with the grinding wheel, serves to effect rotation thereof at prescribed grinding speed.

Supported on the bed 15 is a pair of work rest brackets 29, as particularly illustrated in Figures 4 and 6. Each of these brackets is provided with a slot as at 30 to receive the work rest blade 31 having the inset rollers 32 for supporting the portion of work to be ground as is particularly indicated in Figures 3 and 4. The blades 30 are formed with passages as at 32' to receive the plungers 33, while threaded into the upper portion of these passages are the adjusting bolts 34 coaxing with the plungers for accurate adjustments of the blades and work supporting rollers, set screws 35 being provided for locking the blades in their adjusted position. By reference to Figure 6 it will be noted that the supporting rollers are offset with respect to the work axis in the direction of the grinding wheel so that gravity will tend to force the work toward the regulating wheel in order that the same may properly frictionally engage and effect rotation of the work piece.

Work elevating mechanism

40 Due to the size of the work piece involved they are ordinarily shifted to the machine by a crane or like device, but must then be smoothly placed in position on the work rest blade to avoid springing of the parts of the machine or chipping of the wheel. To effect this result, there are provided rising from the base 15, or its auxiliary regulating wheel supporting section 36, guides 37 for the vertically movable posts 38 to which are pinned the tubular sleeves 39 having at their 45 upper ends the V's or notches 40 for engagement with the work piece. Suitably telescoping shield members 41 are contained between the posts and sleeves to protect the post bearings from grit and coolant during the adjusting movement of the parts. As shown, the posts are provided at their lower ends with the rack portions 42 meshing with the pinions 43 on the actuating shaft 44.

One of these pinions is provided with a second reduced pinion portion 45 engaged by rack 46 on slide rod 47 to piston 48 operating in cylinder 49. By reference particularly to Figure 3 it will be noted that this piston cylinder mechanism is of the differential type, further that pressure against the right hand end of the piston will operate 65 through the rack and pinion mechanism thus described to elevate the sleeves 39 and thus the work piece 50. Similarly, release of pressure against the right hand end will, either by gravity or through weight of the parts cause downward movement of the sleeves 39 until the work is deposited on the rollers 32. There is preferably at least sufficient pressure exerted against piston 48 to retract the notched portions of the members 39 away from the work as indicated in Figure 3.

70 In order that the work may be not only gravita-

tionally, but, in addition, yieldingly or resiliently urged into frictional engagement with the regulating wheel, there have been provided the vertically adjustable brackets 51 secured as by bolts 52 to the face of the base portion 36. These brackets 5 5 bear trunnions 53 on which are pivoted the arms 54 having at their upper ends rollers 55 for engagement with the work piece. At their lower ends these arms are provided with the resilient plunger devices 56 for springing the arms outward 10 about the pivots 53 as respects the lower end of the arms so that the rollers 55 will be moved inwardly. Adjusting stopping devices 57 serve to determine the amount of this inward swinging movement.

15 It will be noted that the slides 39 are provided with the cam plates 58 having beveled terminal portions 59 and 60 for engagement with the release controlling rollers 61 on the arm 54. By reference to Figure 3 it will be noted that when 20 the members 39 are in depressed position that the cams have then moved entirely out of engagement with the rollers. However, as the elevating fixture starts to rise, the portion 59 will engage the adjacent roller 61, camming the arm outwardly about its pivot in a position such that the rollers 55 tend to disengage the work piece prior to its elevating movement by the fixture. Similarly, if the extent of upward movement be 25 considerable, the rollers 61 may again ride down on the portion 60 of the cams so that the members 55 are swung inward toward the regulating wheel to the extent limited by stop 57, the rollers having been reversely swung by interengagement of the parts 69 and 61 as the fixture descends bearing 30 the fresh piece to be machined.

35 It is to be understood that in the grinding of spaced selected portions on a work piece of this type it is necessary that the work be not only properly radially positioned, but also axially located so that the grindings will take place at exactly the proper point in each instance. This is accomplished as shown in Figure 4 by the provision of a pair of substantially U-shaped bracket members 62 and 63 which are also suitably adjustably secured to the units 36 as by fasteners 40. The lateral flanges 62' and 63' of these bracket members serve to supplement the action of the notches in the elevating sleeves 39 so far as lateral positioning of the work is concerned, as it is 45 moved into or out of the throat, while at the same time the end walls have a terminal engagement with the work pieces 50 to insure its proper end-wise position. This may be constantly effected during the grinding operation by providing one 50 of the members, such as 62, with an end thrust block, such as 65, suitably mounted on antifriction thrust bearings 66. As opposed to this, the member 63 is provided with a resilient guide plate 67 which may engage the work during its descent in the guide troughs and may be projected as shown in Figure 4 as a permanent resilient end stop for the work or, by loosening of screw 68, 60 may be retracted in the event that an auxiliary 65 power drive for rotation of the work is to be employed.

Auxiliary power drive

70 The operative position of the auxiliary power drive mechanism with respect to the remainder of the machine has been indicated in dotted lines in connection with Figure 2 and the structural details thereof particularly shown in section in Figure 5. This mechanism comprises a unitary as-

sembly including a main supporting housing 69 and an associated driving motor 70.

Journalized within the housing is the drive sleeve 71 bearing the sprocket 72 driven from motor 70 as by the drive chain 73. Slidably within and keyed to the sleeve 71 is the work driver 74, having at its outer end the head 75 provided with drive pins 76, laterally received in apertures 77 of the floating clutch head 78, said pins being provided with the resiliently pressed washer 79 for yieldingly holding the parts together. The clutch head 78 is of cylindrical form and provided with the clutch jaws 80 adapted to be brought into clamping engagement with the end of the work piece by outward movement of the hydraulically actuated piston 81 contained within the head. This piston is further provided with a yieldingly held washer 82 urgeable into clamping and spring compressing relation with the end of the work piece by movement of the piston. Accordingly, when hydraulic pressure is introduced into the rear of the floating head this pressure will seat the washer against the end of the work piece and further movement will compress the spring, bringing the jaws 80 into clamping engagement therewith while conversely, upon release of this pressure, expansion of the spring will move the piston into the head and at the same time release the pressure of the clamps.

In view of the fact that the work piece must be radially shifted into and out of operative position in a machine, it will be understood that it is necessary that the driving head just described have an axial movement as an entirety to engage and disengage the terminal portion of the work piece. This is accomplished by providing within the housing 69 a cylinder portion 83 in which is slideably mounted the piston 84 coupled with sleeve 74 whereby introduction of pressure into the right hand end of the cylinder will shift the piston, and thus the head, to the left so that the parts will keep the relation illustrated in Figure 5, while introduction of pressure into the opposite side of the piston will retract the parts.

45 *Hydraulic control mechanism*

It is to be noted that the actual operation of the work positioning mechanism and of the engagement and disengagement of the work driving mechanism is effected by employment of a suitable pressure medium, preferably a hydraulic fluid circuit. The circuit diagram of the controls and manner of operation will be particularly understood by reference to Figures 9 and 10. By reference to these it will be noted that there has been provided a suitable fluid reservoir as at 85 from which the fluid may be distributed under pressure as by pump 86 having a pressure line leading to port 87 of valve cylinder 88 containing a spool valve 89 alternatively actuatable as by the manually shiftable control lever 90 or solenoid 91.

Considering the work cycle as starting when a work piece has been deposited in the notches 40 with the members 39 in elevated position, a starting lever 90 is moved to the position shown in Figure 9. The pressure fluid is then coupled by line 92 with the left hand end of cylinder 49, causing piston movement to the right so that the work is deposited in the machine as indicated in connection with Figure 3. At the same time the left hand end of the cylinder is connected through line 93 to the reservoir return lead 94. As the member 39 reaches its lowermost position it trips switch 123 of the electrical control circuit which, as later described, energizes solenoid 96.

moving the clamp control valve 97 to the left, coupling pressure line 87 with the pilot line 98 introducing pressure against the right hand end of valve 99, shifting same to the left. As valve 99 initially moves to the left it places pressure line 100 in communication with line 101, leading to the right hand end of work rotation control cylinder 83, moving the piston therein to the left so that the driving chuck overlies the end of the now deposited work piece. Continued movement of valve 99 to the left uncovers port 102 of conduit 103 and when sufficient pressure has been built up in line 98, due to blocking of free movement of piston 84, this pressure will overcome the resistance of valve 104, allowing the pressure to flow into line 105 which, as shown, is coupled by pipe 106 with rotary coupling 107 with a tube or conduit 108 leading into the cylinder 81 back of the work clamp piston. Accordingly, this piston will be actuated for clamping of the work only after the fixture, as an entirety, has been moved into telescoping relation with the work terminus.

Conversely, at the completion of the grinding operation when the solenoid 96 is de-energized, as will be subsequently described in connection with the electric diagram, spring 109 shifts valve 97 to the position shown in Figure 10, whereupon line 98 is connected to reservoir while the trapped pressure existing at the opposite end will cause a shifting of valve 99 to the right, in turn, coupling pressure line 101 to reservoir when the pressure through line 100 will be exerted through 107 against the left hand side of piston 84, moving same to the right and retracting the driving device out of the path of removal of the work piece.

It is to be understood that the circumferential cannelure of the bushing for valve 97 affords a permanent pressure connection between lines 87 and 100 while the movement of valve 97 determines whether pressure line 87 or existing connection 94 will be effective as respects the pilot line circuit 98.

It is to be noted that the pressure drop effective in line 105 by shifting of valve 99 releases the clamping effect of piston 81 prior to the application of pressure to retract the device as an entirety, and therefore, a proper sequence of telescoping of the parts, gripping of the work and subsequent release and retraction is automatically effected in a simple and efficient manner.

50 *The electrical control system*

This portion of the control of the several movements of the machine is particularly illustrated in Figure 11 in which there has been shown a two wire system comprising the leads 110 and 111, supplying current for operation of the infeed motors 112 and 113 effecting rotation of cams 114 and 115 for oscillating the respective grinding wheel carriages about their trunnions to effect the proper approach and recession of the grinding wheels with respect to the work pieces. To distinguish from their diagrammatic showing in Figure 11 the actual cam element has been indicated in Figure 8 by the numeral 116. It will be noted that extending from the lead 110 is the branch lead 117 coupleable through switch members 118 and 119 respectively with the lead 111 by way of the motors 112 and 113 so that when the switches are in closed position respectively motors will be operated. These switches are normally held in open position as by spring 120, but may be closed by energizing switch solenoid 121, causing movement of the core or armature 122 and thus the

switch members to the right, as viewed in Figure 11.

Energization of the switch solenoid 121 is preferably controlled by a spring opened switch 123 projecting into the path of abutment lug 124 on the work elevator or transfer mechanism 38. As the elevating device is moved into its lowermost position, as indicated in Figure 3, so that the work rests in proper position on the work 10 rest and against the regulating wheel, the switch 123 is closed as indicated in the diagrammatic view. This completes a control circuit from line 110 by way of switch 123, solenoid 121, lead 125, normally closed switch 126 and lead 127 to main 15 line 111. Upon rotation of the infeed motors the rear portions of the two pivoted grinding wheel carriages 25 will be elevated, raising the switch control cams 128, 129, 130 and 131. In depressed position cams 128 and 130 hold in open position 20 the switch devices 132 and 133, and as the cams rise they permit these switch members to engage respectively contacts 134 and 135, completing the branch circuits 136 and 137 for motors 112 and 113 respectively, so that these motors will then 25 continue to function irrespective of the conditioning of such members 118-119.

At the same time that the circuits 132-134 and 133-135 have been completed, corresponding movement of the cam devices 129 and 131 permit 30 of movement of the switch members 138 and 139 which are disposed in series one with the other and serve jointly to complete the circuit through lead 140 having branches, one including the switch solenoid 141 and the other the switch terminals 142. When the circuit 140 is completed, it serves to energize switch solenoid 141 moving the multiple switch device 143 to break the circuit connection at 126 and complete the normally open switch circuits 142 and 144.

40 Opening of switch 126 serves to de-energize solenoid 121, opening switches 118 and 119; closing of switch 142 completes an alternative circuit through solenoid 141 for maintaining same subsequently energized irrespective of the position of contacts 138 and 139; while closing of 45 switch 144 conditions circuit 145 from lead 110 through switch solenoid 146 to contact 147.

The circuit remains conditioned as just described until after completion of the grinding 50 operation. During the reverse or downward swinging movement of the grinding wheel supports 23, cams 129 and 131 will move downwardly as viewed in Figure 11, reacting against the switch members 138 and 139, moving them toward 55 the right to open the series circuit through line 140. Due, however, to the fact that switch 142 is closed, this however, has no effect on solenoid 141 which was initially energized by the closing of this series circuit. Further movement of the 60 members 138 and 139 under the influence of their respective cams serves to complete circuit 145 serially through contacts 147 and 149, energizing solenoid switch 146. This closes the double pole switch 151-152 of solenoid 91 which is coupled 65 with spool valve 89 as previously described. Energizing this solenoid causes reversal of position of the spool and elevation of member 38 moving the work piece upward out of the throat as indicated by the dotted lines in Figure 11. This 70 movement, it will be understood, releases switch 123, breaking the general control circuit and de-energizing the several solenoids, without however in any way effecting the hydraulic actuation of the elevating mechanism, which will continue until the fixture has reached its upper limit of move-

ment, when the work piece may be removed, a new piece of work substituted and the operation of the hydraulic cylinder manually reversed by operation of lever 90.

It will be understood that the foregoing operation is equally applicable whether dependence is placed solely on friction rotation of the work by the regulating wheel or whether the power work drive, previously described and particularly illustrated in connection with Figure 5, is employed.

In the latter event the solenoid 96 is coupled by the leads 154-155 to the leads 140 and switch 138 in parallel with the solenoid switch 141. Consequently, this switch will be closed, moving the hydraulic work rotation clamp control valve to the left, causing proper grasping and actuation of the work as hitherto described and maintaining this condition during the entire inward and partial outward movement of the grinding wheel. It is to be noted, however, that the action of the cams 129-131 on their return movement break the circuit including the coil 96 so that the work will be unclamped and the driving chuck withdrawn an appreciable period in advance of the actuation of solenoid 91, reversing the effect of the carrier so that the entire device will operate in proper synchronism.

What is claimed is:

1. The combination with a machine of the centerless grinder type including a grinding wheel, a regulating wheel and an interposed work rest, of means for controlling the operative positioning of work in the throat thus formed, including an elevating mechanism reciprocable transversely of the throat for receiving work in elevated position as respects the throat and moving same downward into position on the work rest, means adjacent the work rest for resiliently urging the work into engagement with the regulating wheel, and means on the elevating mechanism for controlling the movement of said work engaging means into and out of operative position.

2. The combination with a machine of the centerless grinder type including a grinding wheel, a regulating wheel and an interposed work rest, of means for controlling the operative positioning of work in the throat thus formed, including an elevating mechanism reciprocable transversely of the throat for receiving work in elevated position as respects the throat and moving same downward into position on the work rest, means adjacent the work rest for resiliently urging the work into engagement with the regulating wheel, means on the elevating mechanism for controlling the movement of said work engaging means into and out of operative position, and means operable on descent of the elevating mechanism for initiating the grinding operation.

3. The combination with a grinding machine including a bed or support, a pair of spaced regulating wheels mounted thereon for rotation about parallel axes, a pair of shiftable grinding wheel supports, grinding wheels carried by said wheel supports in opposition to the respective regulating wheels, an elevating mechanism for controlling presentation of a work piece in opposition for grinding of selected portions thereof by the respective grinding wheels, and means actuatable by movement of the work elevating mechanism for effecting individual movement of the respective grinding wheels in the direction of the work.

4. The combination with a grinding machine including a bed or support, a pair of spaced regulating wheels mounted thereon for rotation about

parallel axes, a pair of shiftable grinding wheel supports, grinding wheels carried by said wheel supports in opposition to the respective regulating wheels, an elevating mechanism for controlling presentation of a work piece in opposition for grinding of selected portions thereof by the respective grinding wheels, means actuatable by movement of the work elevating mechanism for effecting individual movement of the respective grinding wheels in the direction of the work, and means actuatable by retraction of the grinding wheels for determining the operation of the elevating mechanism for removal of the work from grinding position.

spaced aligned work receiving throats are provided, a pair of work elevating mechanisms, each individual to one of said work supports, a hydraulically operated mechanism for effecting synchronous movement of the elevating mechanisms whereby a massive elongated work piece may be satisfactorily positioned for simultaneous grinding of spaced selected portions thereof by the respective grinding wheels, means for yieldingly urging the work in a direction toward the regulating wheel, and means on the elevating mechanism for effecting successive toward and from movements of said urging means during unidirectional movement of the elevating mech-

5. The combination with a grinding machine including a bed or support, a pair of spaced regulating wheels mounted thereon for rotation about parallel axes, a pair of shiftable grinding wheel supports, grinding wheels carried by said wheel supports in opposition to the respective regulating wheels, an elevating mechanism for controlling presentation of a work piece in opposition for grinding of selected portions thereof by the respective grinding wheels, means actuatable by movement of the work elevating mechanism for effecting individual movement of the respective grinding wheels in the direction of the work, and means actuatable by retraction of the grinding wheels for determining the operation of the elevating mechanism for removal of the work from grinding position, said means including serially arranged control devices individual to the respective grinding wheel units whereby work retraction is delayed until all grinding wheel units are in retracted position.

9. The combination with a machine of the centerless grinder type including opposed grinding and regulating wheels and interposed work rest forming a three-point contact grinding throat, of means for facilitating grinding of heavy work pieces within the throat, said means including an elevating mechanism disposed adjacent the throat for lateral engagement with a work piece, auxiliary driving mechanism disposed adjacent the throat and movable into position for terminally engaging the work piece, and means operable by movement of the elevating device for effecting operative engagement of the driving device with the work.

10. The combination with a machine of the centerless grinder type including opposed grinding and regulating wheels and interposed work rest forming a three-point contact grinding throat, of means for facilitating grinding of heavy work pieces within the throat, said means includ-

35 grinding wheel units are in retracted position.

6. A machine of the character described, including a pair of spaced work supporting members, regulating wheels individual to the supporting members disposed at one side thereof and grinding wheel units individual to each of said members disposed at the opposite side thereof, whereby spaced aligned work receiving throats are provided, a pair of work elevating mechanisms, each individual to one of said work supports, and a hydraulically operated mechanism for effecting synchronous movement of the elevating mechanisms whereby a massive elongated work piece may be satisfactorily positioned for simultaneous grinding of spaced selected portions thereof by the respective grinding wheels.

70 8. A machine of the character described, including a pair of spaced work supporting members, regulating wheels individual to the supporting members disposed at one side thereof and grinding wheel units individual to each of said members disposed at the opposite side thereof, whereby
75 of a work piece to a grinding wheel including a 70 friction drive wheel for engagement with the periphery of the work piece, a first hydraulically controlled mechanism for moving the work piece into engagement with said friction wheel, a first control device for determining the movement of 75

- said hydraulically controlled mechanism, a second drive device movable into telescoping relationship with the terminal portion of the work piece, hydraulically operable means for moving said drive device, and means operable by movement of the first hydraulically actuated device for controlling the subsequent actuation of said hydraulically operable means for moving the second drive device.
13. A machine for effecting rotary presentation of a work piece to a grinding wheel including a friction drive wheel for engagement with the periphery of the work piece, a first hydraulically controlled mechanism for moving the work piece into engagement with said friction wheel, a first control device for determining the movement of said hydraulically controlled mechanism, a second drive device movable into telescoping relationship with the terminal portion of the work piece, hydraulically operable means for moving said drive device, means operable by movement of the first hydraulically actuated device for controlling the subsequent actuation of said hydraulically operable means for moving the second drive device, said second drive device including a main unit and a portion movable with and relative to the main unit, and a timing device for effecting said relative movement subsequent to the movement of the unit as an entirety.
14. A machine for effecting rotary presentation of a work piece to a grinding wheel including a friction drive wheel for engagement with the periphery of the work piece, a first hydraulically controlled mechanism for moving the work piece into engagement with said friction wheel, a first control device for determining the movement of said hydraulically controlled mechanism, a second drive device movable into telescoping relationship

with the terminal portion of the work piece, hydraulically operable means for moving said device, means operable by movement of the first hydraulically actuated device for controlling the subsequent actuation of said hydraulically operable means for moving the second drive device, said second drive device including a main unit and a portion movable with and relative to the main unit, a timing device for effecting said relative movement subsequent to the movement of the unit as an entirety, and an additional delayed motion mechanism for effecting corresponding movements of said last mentioned parts in reverse order.

15. A machine of the character described including rotary work supporting members, a grinding wheel movable in a direction toward and from said rotary work supporting members for effecting the grinding operation on a work piece supported thereby, a work transfer mechanism shiftable to present a work piece into or out of engagement with said rotary work supporting members, means for effecting an in and out movement of the grinding wheel, and a control mechanism for said parts including a first actuator operable by movement of the work transfer mechanism for initiating movement of the grinding wheel in the direction of the work, additional actuators operable by movement of the grinding wheel for controlling the cycle of operation of the means for movement of the wheel, and means energized by the out or retracting movement of the grinding wheel for reversing the movement of the work transfer mechanism.
